Inventor

Seth E. Clapp

United States Patent Office.

SETH E. CLAPP, OF CAMBRIDGE, ASSIGNOR TO HIMSELF AND CHARLES L. RIDGWAY, OF BOSTON, MASSACHUSETTS.

Letters Patent No. 74,199, dated February 11, 1868.

IMPROVED CORKSCREW.

The Schedule referred to in these Letters Patent and making part of the same.

TO ALL WHOM IT MAY CONCERN:

Be it known that I, SETH E. CLAPP, of Cambridge, in the county of Middlesex, and State of Massachusetts, have invented certain new and useful Improvements in Corkscrews; and I do hereby declare that the following is a full and exact description thereof, reference being had to the accompanying drawings, and to the letters of reference marked thereon.

To enable others skilled in the art to make and use my invention, I will proceed to describe its nature and construction.

The nature of my invention consists in making a joint in the shank of a corkscrew, and combining with the upper part of the shank a sleeve, which may slip down over the joint in such a manner as to prevent the shank from bending while the screw is being turned into the cork. Said sleeve has pivoted to it a short stud, the lower end of which may rest upon the upper edge of the neck of the bottle, while the joint at the upper end of the stud will serve as a fulcrum for the upper part of the shank, which acts as a lever for drawing the cork.

Drawings.

Figure 1 is a perspective view, showing the corkscrew as it appears while the cork is being drawn from the bottle.

Figure 2 is an elevation of the corkscrew, showing it as it appears when ready for insertion into the cork.

In the drawings, B represents the shank of the corkscrew pivoted at L, fig. 1, to the screw proper, C. E is a sleeve, which, when the shank B is brought into line with the screw C, may be pushed downward, so as to cover the joint L, and take the position as shown in fig. 2, in which case it serves to prevent the shank from bending, in the same manner that the sleeve of a parasol prevents the handle from bending. Attached to the sleeve E, by means of the pin K, is the stud F. The use of this stud will be understood by examination of fig. 1. Thus, after I have turned the corkscrew well into the cork, as represented, the sleeve is slipped up beyond the joint, and the shank B is bent over until the lower end of the stud F rests on the top of the bottle, as shown at H. Now, if we continue to press downward upon A, using B as a lever, the cork will be drawn from the bottle. D is a small stud in the shank B, to prevent the sleeve E from sliding too far up the shank.

Having thus described my invention, I will now proceed to set forth my claim.

What I claim as my invention, and desire to secure by Letters Patent of the United States, is—

The sleeve E and stud F, or their mechanical equivalent, in combination with the jointed corkscrew B C, substantially as described, and for the purpose set forth.

SETH E. CLAPP.
